UNITED STATES PATENT OFFICE.

ANDREW J. KARL AND BENJAMIN F. WEBB, OF SISTERSVILLE, WEST VIRGINIA.

TRANSMISSION.

1,400,500.

Specification of Letters Patent. Patented Dec. 13, 1921.

Application filed February 21, 1920. Serial No. 360,518.

To all whom it may concern:

Be it known that we, ANDREW J. KARL and BENJAMIN F. WEBB, citizens of the United States, residing at Sistersville, in the county 5 of Tyler and State of West Virginia, have invented new and useful Improvements in Transmissions, of which the following is a specification.

This invention relates to transmission 10 means of the planetary variable speed type for driving one shaft from a power driven shaft and the principal object of the invention is to provide automatic means for gradually causing the gearing to pick up a load 15 on the driven shaft.

Another object of the invention is to make 20 the gearing of tapered formation with means for shifting a portion of the gearing to set up a wedge action to prevent slipping of the gearing.

A further object of the invention is to prevent backward movement of the gear carrier under the resistance offered by the load.

This invention also consists in certain 25 other features of construction and in the combination and arrangement of the several parts, to be hereinafter fully described, illustrated in the accompanying drawings and specifically pointed out in the appended 30 claims.

In describing our invention in detail, reference will be had to the accompanying drawings wherein like characters denote like or corresponding parts throughout the several views, and in which:

Figure 1 is a longitudinal section of the invention.

Fig. 2 is a section on line 2—2 of Fig. 1.

Fig. 3 is a section on line 3—3 of Fig. 1.

40 Fig. 4 is a section on line 4—4 of Fig. 1.

Fig. 5 is a section on line 5—5 of Fig. 1.

Fig. 6 is a view of the supporting plate for the enlarged ends of the rollers.

Fig. 7 is a view of one of the rollers.

45 Fig. 8 is a view of the internal roller.

In these views 1 indicates the drive shaft and 2 the driven shaft, these shafts being in alinement with their ends abutting. The gearing is inclosed by a frame which consists 50 of the plates 3, which are connected together by the rods 4 and held in spaced relation by the sleeves 5 on said rods. The shafts pass through tubular extensions 6 on said plates.

The driven shaft 2 carries a frusto-conical 55 casing 7 which consists of the end plates 8 and 9 and the cone 10, the end plate 8 being

splined to the shaft. The plate 9 is provided with a screw threaded boss 11 to receive the screw threaded bushing 12 through which the drive shaft passes. A lock nut 13 holds the bushing in adjusted position in the boss. A roller cage is located within the casing 7, said cage consisting of the plates 14 and 15 rotatably carried by the drive shaft, the plate 15 having the hub 16 through which the drive shaft passes and which passes through the bushing 12. This cage carries the frusto-conical rollers 17 which have stub axles 18 on the small ends engaging holes in the plate 14 and their large ends are grooved, as at 19, to receive the ball bearings 20. The plate 15 carries the ball racers 21 for said ball bearings. Thus the rollers are rotatably mounted in the cage by said ball bearings and the stub axles. The rollers are preferably hollow as shown. The rollers are so mounted in the cage that they will project therefrom so as to contact with the inner circumference of the casing 7. A frusto-conical sleeve or roller 22 is splined to the drive shaft 1 within the cage and solid rollers 23 are arranged in the annular space between said sleeves and the rollers 17. Ball bearings 23' are arranged between the inner end of the bushing 12 and the outer face of the plate 15 so that by adjusting the said bushing the pressure between the rollers 17 and the casing may be controlled.

Rollers 24 are placed in cam recesses 25 formed in one of the plates 3 and said rollers engage with the hub 16. These parts are so arranged that backward rotation of the carriage is prevented as if said cage should start to rotate in a rearward direction the rollers would move into the small part of the recesses and thus lock the cage against movement. The outer end of the hub 16 is provided with clutch teeth 26 and a clutch part 27 is carried by the drive shaft 1 and is adapted to be shifted, by any suitable means, into and out of engagement with said teeth so as to lock the cage to the drive shaft when desired.

As will be seen from Fig. 1 the plate 15 of the cage is of greater diameter than the plate 14 and the ball bearings and openings in said plates are arranged to hold each roller in an inclined position and parallel with the walls of the casing 7.

It will thus be seen that when shaft 1 rotates it will carry the sleeve 22 with it and the rotation of this sleeve will be imparted

to the rollers 23 and 17 and as the rollers 17 revolve they will cause the casing 7 to turn in the same direction as the shaft 1 and as said casing is splined to the shaft 2 said shaft 2 will be driven in the same direction as shaft 1. At first the rollers will revolve with the cage held stationary but as the load is picked up the cage will begin to revolve so that the driven shaft will be rotating faster and finally both shafts will be rotated at practically the same speed, provided, of course, that the friction between rollers 17 and casing 7 is greater than the load. When this occurs the clutch 27 may be shifted to engage the clutch part 26 so as to connect the cage with the drive shaft.

If there should be any slipping between the rollers and the outer case this can be taken up by tightening the bushing 12.

It is thought from the foregoing description that the advantages and novel features of our invention will be readily apparent.

We desire it to be understood that we may make changes in the construction and in the combination and arrangement of the several parts, provided that such changes fall within the scope of the appended claims.

What we claim is:—

1. An apparatus of the class described comprising a driven member and a driving member, a roller cage rotatably mounted on the driving member, a casing carried by the driven member and surrounding said cage, rollers carried by the cage and continuously contacting with the inner circumference of the casing and means for rotating said rollers from the driving member in the same direction as that of the said member so as to rotate the cage and the driven member in the same direction as that of the driving member.

2. The combination with driving and driven shafts arranged in end to end relation, a roller cage rotatably mounted on the drive shaft, a casing carried by the driven shaft and surrounding said cage, rollers carried by the cage and continuously contacting with the inner circumference of the casing, a roller keyed to the drive shaft within the cage and rollers located between said keyed roller and the first mentioned roller.

3. In combination with the driving and driven shafts arranged in end to end relation, a roller cage rotatably mounted on the drive shaft, tapered rollers carried by said cage and inclinedly arranged, a frusto-conical casing carried by the driven shaft and having its inner circumference engaging said rollers, a tapered roller keyed to the drive shaft within the cage and rollers located between the said keyed roller and the first mentioned rollers.

4. In combination with the driving and driven shafts arranged in end to end relation, a roller cage rotatably mounted on the drive shaft, tapered rollers carried by said cage and inclinedly arranged, a frusto-conical casing carried by the driven shaft and having its inner circumference engaging said rollers, a tapered roller keyed to the drive shaft within the cage and rollers located between the said keyed roller and the first mentioned rollers and means for keeping the outer rollers in contact with the casing.

5. In combination with driving and driven shafts arranged in end to end relation, a roller cage rotatably mounted on the drive shaft, tapered rollers carried by said cage and inclinedly arranged, a frusto-conical casing carried by the driven shaft and surrounding the cage with its inner circumference engaging the rollers, a roller keyed to the drive shaft, rollers located between said keyed roller and the first mentioned rollers and clutch means for connecting the cage with the drive shaft.

6. In combination with driving and driven shafts arranged in end to end relation, a roller cage rotatably mounted on the drive shaft, tapered rollers carried by said cage and inclinedly arranged, a frusto-conical casing carried by the driven shaft and surrounding the cage with its inner circumference engaging the rollers, a roller keyed to the drive shaft, rollers located between said keyed roller and the first mentioned rollers and means for preventing rearward rotation of the cage.

In testimony whereof we affix our signatures.

ANDREW J. KARL.
BENJAMIN F. WEBB.
